UNITED STATES PATENT OFFICE.

ROBERT HEAD, OF NEW YORK, N. Y., ASSIGNOR TO THE AEOLIAN COMPANY, A CORPORATION OF CONNECTICUT.

AUTOMATIC MUSICAL INSTRUMENT.

1,424,903.

Specification of Letters Patent. Patented Aug. 8, 1922.

Application filed September 10, 1918. Serial No. 253,446.

To all whom it may concern:

Be it known that I, ROBERT HEAD, citizen of the United States, residing at 558 West 164th Street, New York city, N. Y., have invented new and useful Improvements in Automatic Musical Instruments, of which the following is a specification.

My present invention relates to automatic musical instruments and comprises means controlled from the front-end or tab of the music-sheet to operate any desired mechanism in the instrument, such as an automatic rewind mechanism, the latter being the kind of mechanism with which I have chosen to illustrate my invention in the accompanying drawings.

In said drawings, Fig. 1 is a front elevation and diagrammatic view of the music-roll winding and rewinding mechanism of a player-piano embodying my invention; and Figs. 2 and 3 are respectively vertical sections partly in elevation on the lines 2—2 and 3—3 in Fig. 1 looking in the direction of the arrows:

Describing now the devices of the drawings:—1 is the music-roll box containing as usual the end-bearings 2—3 for the music-roll 4; tracker-bar 5; and take-up spool 6 secured to the shaft or spindle 7. The perforated music-sheet is designated 4^a.

8 is the usual pneumatic-motor which may be operatively connected in any suitable or well-known manner through clutch mechanism so as either to drive the music-sheet in playing direction by winding it on the take-up spool; or reversely to rewind it back upon the music-roll spool by driving the latter from the motor. Thus 9 is the clutch-lever pivotally supported at 10. Its lower end is connected by a link 11 with the lever 12 pivotally supported at 13. This lever has lugs at each end supporting laterally projecting pins 14 and 15. 16 and 17 are clutch-operating bellows, whose movable-boards contact with the pins when the bellows collapse to operate the lever 12 and the clutch. Of course the respective bellows are collapsed at different times as will hereinafter appear.

The upper-end of the clutch-lever 9 works in an annularly grooved collar 18 secured to the endwise slidable shaft 19 having its

bearings in the part 20 at the side of the music-roll box 1 and in the bracket 21. 22 is a sprocket-wheel which is secured to the 55 said endwise slidable shaft 19 and is chain-connected to the sprocket-wheel 23 of the motor drive-shaft 24. 25 is another sprocket-wheel loose on the endwise slidable shaft so as to be free to turn thereon but is prevented from movement endwise of the shaft by the fixed finger 26 projecting into the annularly grooved hub of said sprocket-wheel. Chain 27 connects this sprocket-wheel with sprocket-wheel 28 on the drive-spindle 3 for 65 the music-roll.

The aforesaid collar 18 has clutch-pins 29 and 30 projecting from its respective ends to engage respectively with the clutch-pins 29^a and 30^a on the gear-wheel 31 and the 70 sprocket-wheel 25. Said gear-wheel 31 is loose on the endwise-slidable shaft 19 so as to be free to turn thereon but is prevented from movement endwise of the shaft by the fixed finger 32 projecting into the annularly 75 grooved hub of said gear-wheel. This gear wheel is in mesh with the gear 33 on the take-up spool spindle 7.

The operation so far is that whenever the upper bellows 16 is momentarily collapsed, 80 it operates the lever 12 and the connected parts into the position shown in Fig. 1 wherein the motor 8 drives the music-roll spindle 3 to rewind the music-sheet. Vice versa when the lower bellows 17 is momentarily collapsed, it operates the lever to swing the upper-end of the clutch-lever 9 to the left to slide the clutch-collar 18 and shaft 19 also to the left so that its left-hand pin 29 now comes into clutch with the pin on the gear 31 with the result that the motor 8 then drives the take-up spool and winds the music-sheet in playing direction upon said spool.

34 is a duct in the tracker-bar with which 95 the music-sheet perforation 35 registers when the end is reached either of the entire composition or any earlier part of it, as determined by the position of said perforation along the length of the music-sheet. This duct in turn is operatively connected to the upper bellows 16 via the usual valve-box 36 which latter in turn is connected to the suction at 37. It obviously follows that 100

the upper bellows will be collapsed whenever and as long as said sheet-perforation opens said tracker-board duct 34 thereby throwing the clutch-parts into the position 5 shown in Fig. 1 whereby the sheet is caused to be rewound.

Mounted on the side of the music-roll box is a bracket 38 which pivotally supports the valve-lever 39 at 40; and also supports a 10 tubular-nipple 41 whose mouth or port is kept normally closed by the valve-lever by virtue of the leaf-spring 42 acting against the opposite end of the valve-lever. The other end of this nipple 41 is tube-connected, as will be understood from the drawings, with the lower bellows 17 via a valve-box 43 so that whenever and as long as the 15 port of the nipple is opened by the lifting of the valve-lever, said bellows will be collapsed to shift the clutch into reverse position from 20 Fig. 1.

The means for thus lifting the valve is operatively related to the tab 44 or front-end of the music-sheet and comprises the 25 following:—45 is a finger projecting downwardly at right-angles from a rock-shaft 46 supported under the tracker-bar. This rock-shaft projects rotatably through the right-hand cheek of the music-roll box; and outside said box is provided with another finger 47 substantially paralleling the first-named finger. At its left-end said rock-shaft has a bearing in the part 48 secured to underside of the tracker. 49—49 are a pair of spaced 30 stops or lugs on said bearing part which loosely straddle the finger 45 and act as extreme inner and outer limits to its swing. 6^a is the annular recess ordinarily found in take-up spools wherein the hook 6^b is recessed below the peripheral surface of the 35 spool for engagement with the ring or eye 4^b of the music-sheet tab. The aforesaid finger 45 during the playing and rewind, 40 yieldingly rests upon the music-sheet at the place where it is winding about the take-up 45 spool over its aforesaid annular recess 6^a, due to the action of a spring 50. This condition is shown in Fig. 1 wherein a rectangular opening has been cut out of the music- 50 sheet to illustrate it. The same is shown also by the sectional view in Fig. 2. Fig. 3 shows the position at this time of the other finger 47 at the opposite end of the rock-shaft wherein it will be noted it is out of 55 contact with the valve-lever so that the spring 42 is able to keep said valve-lever seated on and closing the mouth of nipple 41. All these figures show the sheet at the end of the rewind with the finger 45 about 60 to ride off the edge of the tab 44 into the recess 6^a of the take-up spool. When this happens, the end of said finger swings into said recess 6^a impelled by the aforesaid spring 50 which simultaneously swings the 65 other finger 47 against the valve-lever 39

lifting its valve off the nipple. This instantly admits atmospheric air to the related valve-box and operates its valve to connect the bellows 17 with the exhaust, thereby collapsing said bellows and reversing the 70 clutch so that the motor now drives the take-up spool and again begins to wind the music-sheet in playing direction. The playing then continues until the rewind-perforation 35 is reached whereupon the clutch is 75 again shifted as previously described to effect rewinding and so on, the automatic repetitions continuing indefinitely until purposely stopped by the operator.

The end of the finger 45 is made so broad 80 that it cannot enter the music-perforations in the music-sheet.

Of course changes and modifications will suggest themselves which will nevertheless be within the spirit of my invention and of 85 the annexed claims.

What I claim is:

1. In combination with an automatic musical instrument using a music-sheet, the front end of the music sheet having an imperforate portion; a take-up spool to which the front end of the music-sheet is attachable and which is adapted to be rotated to take up said sheet, said spool having an annular peripheral recess; a finger at the take-up spool yieldingly tending to move into said recess but being prevented by the said imperforate portion of the sheet when the sheet is wound around said spool; and pneumatic means comprising a controlling 90 port and valve therefor, said valve being operated from the aforesaid movement of the finger relatively to said recess when the latter is uncovered by said imperforate portion of the front end of the music sheet. 95

2. In combination with an automatic musical instrument using a music-sheet,—a take-up spool to which the front-end of the music-sheet is attachable and which is adapted to be rotated to take up said sheet, 100 said spool having an annular peripheral recess; a finger pivoted on a fixed axis adjacent to the take-up spool and yieldingly tending to swing into said recess but being prevented by the sheet when it is wound around said spool; a port with a normally seated valve thereon, said finger when swung within said recess acting to unseat said valve; and means pneumatically controlled from the opening and closing of said port. 110

3. In combination with an automatic musical instrument using a music-sheet,—a take-up spool to which the front-end of the music-sheet is attachable and which is adapted to be rotated to take up said sheet, 115 said spool having an annular peripheral recess; a finger at the take-up spool yieldingly tending to swing by a pivotal movement into said recess but being prevented by the sheet when it is wound around said spool; a port 120

125

130

with a normally seated valve thereon; a rock-shaft supporting the aforesaid finger and rotatable by the pivotal movement of the latter; and another finger supported on 5 said rock-shaft at the valve, so as to operate said valve when the first named finger swings into the recess in the take-up spool

and the rock-shaft is thereby caused to rotate.

In testimony whereof, I, said ROBERT 10 HEAD have signed my name to this specification, this seventh day of September, 1918.

ROBERT HEAD.
